CIGARETTE PACKAGE

Glen S. Stratton, Chicago, Ill., assignor of one-half to Arthur O. Huria, Oak Park, Ill., and one-fourth to Hazel L. Stratton, Omaha, Nebr.

Application January 19, 1933, Serial No. 185,763

4 Claims. (Cl. 206—41)

This invention relates to a package and more particularly it relates to a novel means of packaging cigarettes and the like.

The usual cigarette package holding twenty cigarettes has a number of disadvantages. It is, first of all, rather bulky and when placed in the pocket or a handbag creates an unsightly bulge. Moreover, when some of the cigarettes have been removed, the package soon loses its shape and the remainder of the cigarettes may easily become bent and damaged and lose their freshness. Furthermore, it is impossible to divide a package of cigarettes and sell a part thereof and still keep the remainder fresh and salable.

15 The principal object of the present invention is to overcome these disadvantages by providing a pack of two, three or more separable units which may be easily divided from the whole. Each unit may be separately sold and used. 20 When detached each unit constitutes a complete package. The cigarettes in each unit, both before and after separation, are protected from damage and are maintained fresh and salable. The separate units or several together comprise 25 a convenient pack for the pocket or handbag. This advantage will appeal to purchasers, particularly feminine buyers, who desire a pack which takes up a minimum of space.

The invention has other objects such as the 30 provision of a separable strip package having a relatively stiff backing and in which the cigarettes disposed thereon in groups are covered by a relatively thin moisture-proof, and preferably transparent covering. Means are also provided for facilitating the separation of the units 35 so that only one unit of cigarettes is opened at a time, after which that portion of the package is discarded and the next group is opened, and so on. Moreover, it is an object of the invention 40 to provide a package which, while answering all the requisites, is simple in construction and can be produced at a cost which is not prohibitive to widespread use.

Furthermore, the invention provides a package 45 which can be folded into two or more groups to make units of sale of from say five to twenty-five cents.

Still further, the invention provides a convenient and practical package for use in cigarette vending machines. The present vending machines require two coins but with the present invention a vending machine can be used which requires only one coin, say for a five cent unit.

Other objects of the invention will become 50 more apparent from the following description

when read in connection with the accompanying drawings in which:

Fig. 1 is a perspective view of one embodiment of the invention.

Fig. 2 is a cross section on the line 2—2 of Fig. 1.

Fig. 3 is a plan view of the package of Figs. 1 and 2 opened.

Fig. 4 is a cross section on the line 4—4 of Fig. 3.

Fig. 5 is a cross section on the line 5—5 of Fig. 3.

Fig. 6 is a plan view of the blank used in making the package.

Fig. 7 is a plan view of a modified form of package according to the invention, showing the package open.

Fig. 8 is a plan view of the blank used in making the package illustrated in Fig. 7.

Fig. 9 is a plan view of a package involving five units.

Fig. 10 shows the structure of Fig. 9 when folded.

In the modification according to Figs. 1 to 6 inclusive, the package is comprised of three separable units 2, 4, 6. In making the package a blank such as shown in Fig. 6 is first cut from relatively stiff paper or the like and the blank is scored along the dot-dash lines. The upper ends 2', 4' and 6' of the units are folded upwardly and forwardly along the lines a and b, and the lower ends 2'', 4'' and 6'' are likewise folded along lines c and d. The lateral edges of the ends 2'', 4'' and 6'' are folded upwardly. The side edges 8 and 10 of the sections 2 and 6 are folded inwardly.

Cigarettes 11 are disposed in each unit so that they run transversely of the blank as shown in Fig. 3. Where the package is made up of three units, preferably there are seven cigarettes to the unit since this makes for a neat package each unit of which contains the same number of cigarettes. Of course, the unit may contain any desired number of cigarettes. The cigarettes are placed so that the ends 2', 4' and 6' cover their upper ends and so that the lower ends 2'', 4'' and 6'' cover a goodly portion of the lower ends of the cigarettes.

After the cigarettes have been so positioned, the front of the package is covered with a layer of relatively thin material which may be a transparent moisture-proof material or the like. The package as thus covered is shown in Figs. 3 and 4, the layer of covering material being indicated in Fig. 4 particularly by the reference numeral 12.

As shown in Fig. 4, the covering material extends from the edge 8 on the left over the units 2, 4 and 6 to the edge 10 on the right. It is secured to the edges 8 and 10 and also to the portions 14 and 16 of the front of the backing between the units 2, 4 and 6. The covering material also is secured to the ends 2', 4' and 6', and 2'', 4'' and 6'' (see Figs. 3 and 5) but not, of course, to the cigarettes on the units.

10. The covering material may also extend partially or completely over the back of the backing material so as to enclose the cigarettes and the backing material together. The covering material in such instance is preferably secured to
15 the back of the backing as well as to places on the front of the backing strip already specified.

The covering material and the backing material are then perforated on lines 18 and 20 at the intermediate portions 14 and 16 respectively between the units 2, 4 and 6, so that the units may be separated from one another for separate sale or use.

The covering material 12 may be a cellulose product such as Cellophane, or may be a thin film of deodorized rubber which may be secured to the backing without the use of an adhesive. Other materials will suggest themselves.

The package as shown open in Fig. 3 is folded together to form the completed package of Figs. 1 and 2. In, folding, the section or unit 2 is folded over the unit 4 and then the unit 6 is folded over both the units 2 and 4. To render this possible the intermediate space 14 is made the width of two cigarettes or slightly greater while the intermediate space 16 is made the width of three cigarettes or slightly larger.

The package may be made up of any number of separable units. Where, for example, a five unit package is made according to the invention, the space between the first two units would be the width of two cigarettes; the space between the second and third would be the width of three cigarettes. The space between the third and fourth units should be about the width of one fourth a cigarette so that the fourth unit can be folded back over the third unit; and the space between the fourth and fifth units would be the space of two cigarettes. Such a five unit pack can be made to be sold for twenty-five cents complete; or five cents a unit.

The completed package disclosed in Fig. 3 may be secured together by securing the edge 10 to the outer side of the intermediate space 14 as indicated by 22 in Fig. 2. Other ways of holding the completed package together will suggest themselves. The whole package may be wrapped in a transparent or other covering to insure the freshness of the cigarettes.

63 The package as shown in Fig. 1 is sold to the
retailer as such who may then resell the com-
plete package or may open it and separate one
or more units and sell them. If the package is
sold in completed form, the purchaser may carry
64 it all and separate it a unit at a time as the
cigarettes of each unit become depleted. As the
cigarettes become depleted and units are de-
tached, the package becomes progressively small-
er and the cigarettes in the remaining units are
70 kept fresh and protected from crumbling or
breaking.

The purchaser may desire to carry with him only a comparatively few cigarettes. With the present invention it is not necessary to open and expose all the cigarettes in the package since

each unit forms a complete package in and of itself.

The embodiment of the invention illustrated in Figs. 7 and 8 is generally similar to that described above. The blank is shown in Fig. 8 as consisting of three units 102, 104, 106. The units are separated by spaces 114 and 116. The embodiment differs from that of Figs. 1 to 6 in that separate end pieces 152, 154, 156 and 152', 154' and 156' are provided. It is not essential, however, that the lower ends 152', 154' and 156' be separated from the backing. They may be similar to the upper ends 2', 4' and 6' of the embodiment of Figs. 1 to 6.

After the cigarettes 111 are placed on the blank in the units the separate end pieces are placed as shown in Fig. 7 and strings or threads or the like 162, 164, 166 are placed over the upper ends of the cigarettes. A transparent or other covering 112 similar to that of the first embodiment is then secured in place from the edge 108 to the edge 110. It is secured at the intermediate spaces 114 and 116, and also over the separate ends 152, 154, 156 and 152', 154', 156'. The covering 112 is wider than the height of the package and is secured to the upper and lower back edges of the backing of the package. It may, if desired, extend completely over the back of the backing.

Perforations 118 and 120, or other means to facilitate separation of the units, are provided in the intermediate spaces 114 and 116. These pass through the covering 112 as well as the backing formed by the blank. The package is folded up in a manner similar to that shown in Figs. 1 and 2, and may likewise be covered with transparent material, foil or paper covering to protect the contents from damage and moisture.

The units may be separated as in the first embodiment described. The threads 162, 164, and 166 are shearing threads the free ends of which when pulled will shear the covering material between the ends 152, 154, 156 and the backing and thus open the upper ends of the units so that cigarettes may be removed. 45

The structure shown in Fig. 9 is comprised of the five units, 202, 204, 206, 207 and 209, which are formed from a blank from which upper ends 202', 204', 206', 207' and 209' are folded over in the manner previously described, as are the lower ends 202'', 204'', 206'', 207'' and 209''. The side units 208 and 210 correspond to the units 8 and 10 of Figs. 1 to 6. The cigarettes 211 are contained in the units which are spaced as follows: The space 214, which is between units 202 and 204, has approximately the width of two cigarettes. The space 216 between units 204 and 206 is approximately of a width equal to three cigarettes, whereas the space 217 between units 206 and 207 is one-fourth of the width of one cigarette. The space 219 has a width equal to two cigarettes. Tear lines 218, 220, 221 and 223 are provided between the units. When this package is folded, the unit 202 overlies the unit 204 and the unit 206 overlies both the units 202 and 204. The unit 207 is folded back of unit 206 and unit 208 overlies the unit 207 in face to face relation as shown in Fig. 10.

It is believed that the advantages of the invention will be apparent from the objects and description given and need not be elaborated. Obviously, changes may be made in the package without departing from the invention. The embodiments illustrated and described are exam- 75

ples only. The invention is not limited thereto except as indicated in the claims.

Having now described the invention, what I contend is new and desire to protect by Letters 5 Patent is set forth in the following claims.

I claim:

1. A package for cigarettes or the like comprising, a backing strip of relatively stiff paper, five spaced groups disposed thereon with the 10 cigarettes of each group running transversely of the strip, a moisture resistant covering of relatively thin material extending over the front of the strip and enclosing the cigarettes and secured to the edges of the strip and to the intermediate spaces between the groups of cigarettes, 15 means running transversely of the strip at the intermediate spaces for facilitating a severance of the strip into separate units each of which forms a completed package of a group of cigarettes, the intermediate space between the first and second group being substantially equal to the thickness of two cigarettes, the intermediate space between the second and third group being substantially equal to the thickness of three cigarettes, 20 the space between the third and fourth groups being substantially equal to one-fourth of the thickness of a cigarette, and the space between the fourth and fifth groups being substantially equal to the thickness of two cigarettes, 25 whereby the strip may be folded before separation with the first group overlying the second group, the third group overlying the first and second groups, the fourth group folding back to back with the third group and the fifth group overlying the fourth group face to face.

2. A cigarette package for cigarettes or the like comprised of an elongated, substantially rectangular backing strip of relatively stiff, moisture resistant paper, groups of cigarettes disposed on said backing strip with the cigarettes of the groups running transversely of the backing strip, a covering strip of relatively thin, tough, flexible, moisture resistant, transparent material extending over the front of the backing strip and enclosing the groups of cigarettes thereon, said covering strip being secured to the edges of said backing strip and the portions of the backing strip intermediate the groups of cigarettes, thereby enclosing each of said groups on all four sides, the portions of said package intermediate the groups being adapted for severance whereby a group of cigarettes may be separated from the remainder of the package, leaving the remainder of the package intact, the distance between the groups being sufficient to permit the folding of the package with one group superimposed on another whereby the cigarettes, when the package is folded, are protected against

crushing by the respective portions of the backing strip immediately therebehind and by the portion which lies intermediate the groups when the package is unfolded.

3. A cigarette package for cigarettes or the like comprised of an elongated, substantially rectangular backing strip of relatively stiff, moisture resistant paper, groups of cigarettes disposed on said backing strip with the cigarettes of the groups running transversely of the backing strip, a covering strip of Cellophane or the like extending over the front of the backing strip and enclosing the groups of cigarettes thereon, said covering strip being secured to the edges of said backing strip and the portions of the backing strip intermediate the groups of cigarettes, thereby enclosing each of said groups on all four sides, the said backing and covering strips being weakened along coinciding lines extending transversely of said strips intermediate the groups of cigarettes whereby a group of cigarettes may be separated from the remainder of the package, leaving the remainder of the package intact, the distance between the groups being sufficient to permit folding of the package with one group superimposed on another whereby the cigarettes, when the package is folded, are protected against crushing by the respective portions of the backing strip immediately therebehind and by the portions which lie intermediate the groups when the package is unfolded.

4. A cigarette package for cigarettes or the like comprised of an elongated, substantially rectangular backing strip of relatively stiff, moisture resistant paper, three groups of cigarettes disposed on said backing strip with the cigarettes of the groups running transversely of the backing strip, a covering strip of Cellophane or the like extending over the front of the backing strip and enclosing the groups of cigarettes thereon, said covering strip being secured to the edges of said backing strip and the portions of the backing strip intermediate the groups of cigarettes, thereby enclosing each of said groups on all four sides, the portions of said strips intermediate the groups being adapted for severance whereby a group of cigarettes may be separated from the remainder of the package, leaving the remainder of the package intact, the distance between one pair of adjacent groups being greater than the distance between the other pair of groups to permit folding of the package whereby the cigarettes, when the package is folded, are protected against crushing by the respective portions of the backing strip immediately therebehind and by the portions which lie intermediate the groups when the package is unfolded.

GLEN S. STRATTON.
